BRASSIÈRE DEVICE

Lilly Daché, New York, N. Y.

Application March 16, 1948, Serial No. 15,219

1 Claim. (Cl. 2—42)

1

This invention relates to brassière devices and is herein disclosed in some detail as embodied in a device adapted to serve as a brassière with dresses cut so low or "decolleté" in front that a front connection between the two breast elements would be conspicuous and undesirable.

In the form shown, the device includes a resilient bowed holding band member having substantially hemi-spherical ends so that the resilient member is supported partly by lying against the wearer's back and partly by the spring action of the hemi-spherical ends, the whole device covering about 300° of a circle.

In one embodiment device may take the form of a camisole attached brassière, so that the camisole becomes part of a combined garment and brassière, helping to hold the band member in effective and comfortable position.

Thus, a desirably attractive outer garment may be worn low cut at its front center, while the comfortable brassière portion may be firmly maintained in position, with the result that the wearer can be assured against accidental displacement.

In the accompanying drawing:

Fig. 1 shows a camisole combined with the brassière device and carrying attached garters;

Fig. 2 is a cross-sectional view on line 2—2 of Fig. 1;

Fig. 3 shows a separate brassière device;

Fig. 4 is a front perspective view of the frame structure used in the foregoing embodiments;

Fig. 5 shows one form of adjustable frame structure, which may be used in place of the structure of Fig. 4.

The frame structure shown includes a continuous resilient strap or band 10, having a back section 11, which is nearly straight, merging at its ends 12 into sections 13 which turn more sharply to lie under the arms of a wearer, and then bend toward each other at 14, ending in roughly circular rings 15.

In the form shown, the strap splits at or near the bends 14, into upper and lower fork members 16, 17, so that the upper fork member 16 carries its ring 15 near the center frame portion 13 adapted to lie nearly flat on the body.

The portion 18, perhaps a third of the diameter of the ring 15 merges at each end into an almost completely circular section 19, adapted to surround the breast on that side, and serves as a form on which a cup-shaped embracing member 20 is usually sewn. Accordingly, the members 20 are anteriorly spaced from each other and define the respective ends of the band and therefore of

2

the device itself so that no connections between the members 20 are apparent when a dress is worn over the device and is cut very low in front. The brassière may be applied by merely passing it around the back and disposing the members 20 over the breasts, whereupon the resiliency of the band 10 will maintain the device in place with no other connection or supporting device required. The normal diameter of the substantially circular structure is such that the members 20 are clasped to the breasts when applied to the wearer. Thus the resilient band produces an inward force on the members which provide such clasping action.

15 The metal, or other resilient structural support is shown in Fig. 3 as including, if desired, an adjusting device 21. To provide the adjusting device, the strap 10 is shown as two overlapping sections 22, 23, terminating in fingers 24 and 25, bent over on each section to embrace the other section. Thus two guides are provided so that the sections slide on each other without lost motion.

20 The device so far described, preferably omitting the slides 24, 25, is well adapted to be held in the top seam 26 of a camisole 27.

In the form shown, the camisole 27 serves to carry adjustable front elastic garters 28, 29, and rear elastic garters 30, 31. The front garters 28, 29, are attached at the ends of relatively inelastic seams 32, 33, and the rear garters 30, 31, are attached at the ends of relatively elastic seams 34, 35.

25 The seams 32, 33, 34, 35, form the edges of fabric panels, united by seams indicated at 36, 37, 38, 39, 40, 41, of a conventional type to secure the usual distribution of elasticity and vertical pull in a flaring garment.

30 In the form shown, the edges 42, 43, of the camisole are adapted to be drawn together by a lacing 44, passed through eyelets conventionally shown at 45.

The device of Fig. 4 is generally covered with a soft cotton textile 10a as illustrated in Fig. 3, so as to be comfortable to the wearer.

35 The relatively low fork members 16 permit the arm holes of a dress worn over the device to be cut low so as to further enhance the attractiveness of an ensemble. The cup shaped members 20 may be of flexible textile, shaped by a radial seam 46, or may be stiff and self-supporting as far as shape is concerned.

40 The camisole is shown enclosing substantially the whole of the strap 10 to the forking of members 16 and 17 then cut down to the top of edges

42 and 43, and then cut to enclose the members 16 and 17 as a separate unit.

The brassière of Fig. 3 may be worn in place of a conventional brassière and it will serve the functions and purposes set forth hereinabove. If the adjustable elements shown in Fig. 5 are used in the brassière, the fingers 24 and 25 may be permanently clamped down over the sections 23, 23 when a proper fit has been determined. This is an optional expedient and if desired, the sliding arrangement may be retained.

Having thus described certain forms of the invention in some detail, what is claimed is:

A brassière device including a two part resilient band adapted to lie partly against the back of the wearer, said parts overlapping at their ends, each end slidably embracing the other, each part bending forward at its other end and continuing in an upper and a lower fork member, each lower fork member attached to a nearly straight vertical portion of wire near its bottom, each associated upper fork member attached to said wire near the middle thereof, and extensions of the wire being joined to form two nearly circular rings for serving as supports for cup shaped members, said rings being spaced and disconnected

from each other at the front of the device and defining the ends thereof.
